UNITED STATES PATENT OFFICE.

CLIFTON W. SHERMAN, OF BUFFALO, NEW YORK.

SIDE FRAME FOR CAR-TRUCKS.

1,246,169.

Specification of Letters Patent. Patented Nov. 13, 1917.

Application filed January 25, 1916, Serial No. 74,126. Renewed September 25, 1917. Serial No. 193,194.

To all whom it may concern:

Be it known that I, CLIFTON W. SHERMAN, a citizen of the United States, residing at Buffalo, in the county of Erie and State of New York, have invented new and useful Improvements in Side Frames for Car-Trucks, of which the following is a specification.

This invention relates to a side frame for car trucks and has for its object the provision of simple and reliable means which permit of quickly and efficiently connecting each column or yoke with the spring plank and a longitudinal bar of the frame, such as the tie bar and lower arch bar.

In the accompanying drawings:

Figure 1 is a side elevation of a car track provided with my improved side frame. Fig. 2 is a fragmentary vertical longitudinal section of the same, on an enlarged scale, taken on line 2—2, Fig. 3. Fig. 3 is a vertical cross section taken on line 3—3, Fig. 2. Fig. 4 is a horizontal section taken on line 4—4, Fig. 2. Fig. 5 is a fragmentary vertical transverse section, taken on the correspondingly numbered line in Fig. 2.

Similar characters of reference indicate corresponding parts throughout the several views.

1 represents the upper longitudinal arch bar and 2 the lower longitudinal arch bar arranged below the upper arch bar, the central parts of these bars being separated from each other and arranged horizontally while the corresponding ends of these bars converge toward each other and are secured to the upper side of one of the journal boxes 3 in which the axle of the adjacent wheel 4 turns.

5 represents the horizontal tie bar which is arranged with its central part underneath the straight central part of the lower arch bar while its opposite ends are secured to the undersides of the journal boxes, as shown in Fig. 1.

6 represents the spring plank resting at each end on the upper side of the straight central part of the lower arch bar, 7 the springs supported at their lower ends on said plank through the medium of the interposed wooden cushion block 8, and 9 the bolster resting at each end by means of an

interposed wooden cushion block 10 on the upper end of these springs.

11 represents two columns or yokes which are arranged on opposite sides of the spring plank and bolster and form part of the means for connecting together the tie and arch bars and the spring plank and also guiding the bolster.

In its preferred form, each of these columns is provided with a horizontal longitudinal opening 12 the upper end 13 of which forms a downwardly-facing seat and is provided with an upper locking opening 65 or socket 14, extending through said upper seat, while the lower end 15 of said longitudinal opening forms an upwardly facing seat and is provided with a lower locking opening or socket 16 extending through said lower seat, and said column being also provided at its lower end adjacent to the inner side of said lower seat and locking opening with an inclined face 17.

The upper arch bar is arranged in the upper part of the longitudinal opening of each of said columns and bears against the upper seat thereof while the lower arch bar and tie bar are arranged in the lower part of said opening and the tie bar rests on the lower seat thereof. The upper arch bar is provided with a vertical locking opening 18 in line with the upper locking socket and the lower arch bar and tie bar are provided with vertical locking openings 19, 20, which are arranged in line with each other and with the lower locking socket.

21 represents locking and guiding blocks one of which is arranged in the upper part of the longitudinal slot of each column and bears against the underside of the upper arch bar and is provided with an upwardly-projecting locking pin 22 which engages with the adjacent locking opening of the tie bar and the upper locking socket of the respective column. At the outer side of the longitudinal opening in each column, the same is provided with a cross piece or abutment 23 which is engaged by the outer side of the locking-block. The inner side of the latter is engaged by the adjacent outer side of the bolster which moves vertically relatively thereto and is guided in this movement by guide lugs 24, 24, arranged on the

bolster and embracing the inner part of the guiding and locking block. The latter is held in place by a horizontal retaining rod 25 which passes transversely through the 5 locking and guiding block and the column and also preferably serves as a support for the hangers 26 on which the brake shoes 27 for the wheels are mounted.

On opposite sides of the lower part of the 10 longitudinal slot of each column, the same is provided on its inner side with bearing lugs 28, 28, which engage with the adjacent part of the outer side of the spring plank and hold the latter in the proper position 15 relatively to each other when assembled.

29 represents a bracket secured by rivets 30 or otherwise to the outer side of the spring plank between the bearing lugs 28 and bearing against the upper side of the lower arch 20 bar and provided with a depending lower locking pin 31 which enters the corresponding locking openings of the lower arch bar, tie bar and the lower locking socket. At its 25 lower end the lower locking pin is provided with a beveled or inclined face 32 which is adapted to engage the lower inclined face of the companion column.

In assembling the parts of the side frame, the lower arch bar is first placed on the tie 30 bar and then the columns or yokes are placed on these bars about half way between the center line of the journal boxes and the center line of the bolster. While these parts are in this position it is possible to slip the 35 upper arch bar readily into the upper parts of the columns and also to place the spring plank, springs and bolster between the central parts of the upper and lower arch bar. The columns are now driven against opposite 40 site sides of the spring plank, so that the inclined faces of the columns engage with the inclined faces of the lower locking pins and lift the latter and the parts connected therewith and then permit the lower locking pins 45 to drop into the lower locking openings and socket of the lower arch bar, tie bar and column. By this means, the columns are coupled with the spring plank without necessitating jacking up of the latter for this 50 purpose and also permits the several castings to be made nearer to size and still secure a driving fit between the arch bars and tie bar and the columns.

After the lower parts of the columns have 55 been thus connected with the spring plank and lower arch and tie bars, the locking blocks are applied to the bolster and the upper arch bar and upper parts of the columns and then the several bars are secured to the 60 journal boxes.

I claim as my invention:

1. A side frame for car trucks, comprising a longitudinal bar having a vertical opening, a column provided with a horizontal

opening which receives said bar and with a 65 vertical socket, a spring plank arranged above said bar, and a locking pin mounted on said plank and projecting through said opening of said bar into the socket thereof.

2. A side frame for car trucks, comprising 70 a longitudinal bar having a vertical opening, a column provided with a horizontal opening which receives said bar and with a vertical socket, a spring plank arranged above 75 said bar, and a locking pin mounted on said plank and projecting through said opening of said bar into the socket thereof, said pin and column being constructed to produce a wedge action between these parts upon moving the column toward said plank. 80

3. A side frame for car trucks, comprising a longitudinal bar having a vertical opening, a column provided with a horizontal opening which receives said bar and with a vertical socket, a spring plank arranged 85 above said bar, and a locking pin mounted on said plank and projecting through said opening of said bar into the socket thereof, said pin and column being provided with coöperating inclined faces which engage 90 with each other upon moving said column toward said plank.

4. A side frame for car trucks, comprising a longitudinal bar having a vertical opening, a column having a horizontal opening 95 which receives said bar, a vertical socket below said bar and an inclined face adjacent to the inner side of said socket, a spring plank arranged above said longitudinal bar, and a bracket secured to the outer side of 100 said plank and provided with a depending locking pin which engages with said socket and which has an inclined face at its lower end adapted to be engaged by said inclined face of the column upon moving the latter 105 toward said plank.

5. A side frame for car trucks, comprising a longitudinal bar having a vertical opening, a column provided with a horizontal opening which receives said bar and with a 110 vertical socket, a spring plank arranged above said bar, and a locking pin mounted on said plank and projecting through said opening of said bar into the socket thereof, said pin and column being provided with 115 coöperating inclined faces which engage with each other upon moving said column toward said plank and said column being provided with bearing lugs engaging with the outer side of the spring plank. 120

6. A side frame having a column provided with a horizontal longitudinal opening, an upwardly-facing seat at the lower end of said opening, an upwardly-opening locking socket arranged on said seat, and an inclined 125 face adjacent to the inner side of said seat, a tie bar arranged in said horizontal opening and resting on said seat and having

a locking opening in line with said locking socket, a lower arch bar arranged in said longitudinal opening and resting on said tie bar and having a locking opening in line with said locking opening and socket of the column and tie bar, a bracket arranged in the longitudinal opening of said column and secured to the outer side of said spring plank

and having a depending locking pin arranged in said locking openings and socket 10 of the lower arch bar, tie bar and column and provided with an inclined face at its lower end which is adapted to engage the inclined face of the column upon moving the latter toward said plank.

CLIFTON W. SHERMAN.
